UNITED STATES PATENT OFFICE.

MILTON H. SHOENBERG AND LESTER SCHON, OF SAN FRANCISCO, CALIFORNIA; SAID SCHON ASSIGNOR TO SAID SHOENBERG.

CIRCUIT INTERRUPTER.

Application filed November 22, 1924, Serial No. 751,517. Renewed May 3, 1926.

Our invention has for its object a device adapted to fit within a conventional electric service socket and to be introduced in series between a terminal of a socket device, such as a lamp plug or the like, and a terminal of the socket.

Our invention includes thermal actuated means for making and breaking the circuit periodically and is actuated by the heat generated by the flowing current during the period of circuit conductivity. The heat so generated acts upon a thermal element in series in the circuit and causes the separation of contacts thus interrupting the flow of current; thereafter the said element cools and the contacts again come together thus completing the circuit. The flow of current which is now established again heats the thermal element so that there is a continuous alternating making and breaking of the circuit and consequently an alternating energization and de-energization of the device connected in the socket.

The invention herein set forth is an improvement on that shown in Patent No. 1,400,914 issued December 20, 1921.

By referring to the drawing our invention will be understood.

In the drawing, Fig. 1 is a fragmentary cross section of a conventional socket showing our interrupter in position and in series with a lamp with the circuit connections shown diagrammatically.

Fig. 2 is a sheet of insulating material adapted to be positioned between the terminals of our interrupter.

Fig. 3 is an enlarged view of our interrupter.

Fig. 4 shows a heating coil wound upon a strip of insulating material.

Fig. 5 is a cross section of the two halves of the interrupter with the thermostat element and insulating sheet about ready for assembling.

Fig. 6 is an inside view of one of the halves of the insulating material of which the casing of the interrupter is formed.

Fig. 7 is one of the thermostat plates.

Fig. 8 is a side view of the heating coil of Fig. 4 with the insulating strip bent ready for assembling.

Fig. 9 is a second thermostat plate.

Fig. 10 shows the thermostat element complete and consisting of the two plates with a heating coil therebetween and with

the resistance wire and binding thread shown in cross section. The thermostat plates and contacts being in the position corresponding with room temperatures.

Fig. 11 is a side view of the thermostat element of Fig. 10 with the contacts separated corresponding with a period of interruption when the thermostat plates have been raised in temperature by the heating coil.

Throughout the figures similar numerals refer to identical parts.

A conventional socket is shown at 1 energized from the conductor 2, the other terminal of which is shown at 3 energized from the circuit leg 4. At 5 is the filament of a conventional lamp having the circuit button 6 and the metallic shell 7. Where our interrupter is not employed the button 6 contacts normally with the button 3 thus energizing the lamp from the leads 2 and 4.

The casing of one of our interrupter buttons is shown at 8 and this consists of the similar halves 9 and 10 held together by any suitable means as the eyelets 11 and 12 and having the external contact buttons 13, 14 respectively. These two halves or insulating discs form in effect a body of insulating material having a recess within which is disposed a thermostat or circuit interrupter element, this element serving to repeatedly interrupt or vary current supplied to the socket. The contacts 13 and 14 being mounted upon opposite sides of the body member, are insulated from direct electrical contact with each other. The body is able to withstand the pressure of the lamp plug since the recess occupies only a minor portion of its cross sectional area as measured along a plane parallel to the faces of the body.

These buttons are formed preferably by a drop of solder in eyelets 15, 16 respectively which are set in the casing halves 10 and 9. The halves 9 and 10 are each molded with a recess 17 for receiving the thermostat element and a shallower recess 18 adapted to receive an insulating plate 19, to provide the requisite insulation between the eyelets 15, 16, and buttons 13, 14, and conductors 20, 21, leading from the assembled thermostat element in the recess 17.

At 22 and 23 respectively are two thermostat plates each comprising a strip of two metals fixed together. The inside portion of each strip (see Fig. 10) is of brass and

the outside metal of each of the strips is steel. Because of the different coefficient of expansion of the metals of which these plates are made, the plates will become distorted under temperature changes. On the end of each of these plates is a contact point 24, 25, respectively and between the plates is a heating coil 40 having terminals 26, 21, respectively and wound upon a strip of insulating material 27. The ends of this strip are extended as shown in Fig. 4 and subsequently bent over as shown in Fig. 8 to provide electric insulation between the heating coil and the thermostat plates.

15. The terminal 26 is connected with the plate 22 and a connection 20 is made with the plate 23. The two plates 22, 23, with the heating coil therebetween are pinched together and wrapped with thread 41 as shown in Figs. 10 and 11, and a drop of suitable varnish serves as an insulating binder. The completed thermostat element being as shown in Fig. 11. The terminal 20 is now passed through the eyelet 15, the terminal 21 is passed through the eyelet 14. The plate of insulation 19 is placed in position and the two halves 9 and 10 are now brought together with the thermostat element fitting in the socket formed by the recesses 17-17.

20. Binding eyelets 11 and 12 are now fixed through the plates 9 and 10 and a drop of solder at 13 and another at 14 filling the eyelets 15 and 16 provides the terminal connections for the leads 20, 21, with a sufficient button surface projecting from the surfaces of the halves of the casing 9 and 10 as shown by dotted lines in Fig. 5 and these provide contact points when employed in the socket as shown also in Figs. 1 and 3.

25. We claim:

1. A thermostat comprising a pair of opposed plates, each plate having a contact point at one end and formed of two metals of different coefficients of expansion an insulated resistance coil between the other end of said plates and one terminal of said coil connected to one of said plates, a binding compressing said plates against said insulated resistance.

2. A thermostat comprising a pair of opposed plates each plate having a contact point at one end and formed of two metals of different coefficients of expansion an insulated resistance coil between the other end of said plates and one terminal of said coil connected to one of said plates, a binding compressing said plates against said insulated resistance, said insulated resistance coil consisting of a wire wrapped about the end portion of a strip of insulation material and the ends of said material then folded right and left providing an external covering of insulation on each side of said wire.

3. A circuit interrupter comprising a pair of discs of insulating material fixed together

and each having a central contact button, a thermostat as set forth in claim 1 and positioned in a recess in said discs wherein the terminals of the said resistance coil are respectively fixed to the said buttons. 70

4. A circuit interrupter comprising a pair of discs of insulating material fixed together and each having a central contact button, a thermostat as set forth in claim 2 and positioned in a recess in said discs wherein the terminals of the said resistance coil are respectively fixed to the said buttons. 75

5. A circuit interrupter of disc form having a central contact button on each side, a thermostat as set forth in claim 1 in series 80 with said buttons, and a sheet of insulation between said buttons.

6. A circuit interrupter of disc form having a central contact button on each side, a thermostat as set forth in claim 2 in series 85 with said buttons, and a sheet of insulation between said buttons.

7. A thermostat comprising a pair of opposed plates each plate having a contact point at one end and formed of two metals 90 of different coefficients of expansion a resistance interposed between the other ends of said plates, a binding compressing said plates against said resistance.

8. A circuit interrupter comprising a pair 95 of discs of insulating material a thermostat as set forth in claim 7 interposed between said discs and positioned in a recess therein, a central contact button on each of said discs and connections to one of the plates and one button on the one side and the other plate and the other button on the other side.

9. A circuit interrupter comprising a pair of discs of insulating material a thermostat as set forth in claim 1 interposed between said discs and positioned in a recess therein, a central contact button on each of said discs and connections to one of the plates and one button on the one side and the other plate and the other button on the other side. 100

10. A circuit interrupter comprising a pair of discs of insulating material each having a recess, said recess adapted to register forming a thermostat chamber, a thermostat as set forth in claim 7 positioned in said chamber, a central contact button on each of said discs one of said buttons connected to one of said plates and the other button connected to the other plate, and means securing the two discs together. 105

11. A device of the class described adapted to be removably positioned within a lamp socket comprising a relatively flat disc having a recess offset from the center of the same, and an interrupter element operatively disposed within said recess for periodically interrupting current supplied to the socket. 110

12. A device of the class described adapted to be removably positioned within a lamp 115

socket comprising a pair of insulating discs, means for securing said discs together, said discs having a recess formed between their outer faces, and an interrupter element disposed within said recess for periodically interrupting current supplied to the socket.

13. A circuit interrupter adapted to be removably positioned within a lamp socket and comprising a pair of discs of insulating material fixed together and each having a central contact button, an interrupter element disposed within a recess in said discs for periodically interrupting current supplied to the socket, and means for electrically connecting said interrupter element to said contact buttons.

14. A device of the class described adapted to be wholly inserted within a lamp socket comprising a disc, a pair of contacts arranged at opposite sides of said disc, said disc being cut away to provide a cavity between its center and outer periphery, an interrupter element disposed within said cavity for periodically interrupting current supplied to the socket, and means for electrically connecting said interrupter element to said contacts.

15. A device of the class described adapted to be removably inserted within a lamp socket, a pair of relatively flat members secured together to form a disc shaped housing, an interrupter element disposed within said housing for periodically interrupting current supplied to the socket, separate electrical contact elements secured to external faces of said members, and means for elec-

trically connecting said contact elements to said interrupter element.

16. A circuit interrupter adapted to be removably positioned within a lamp socket comprising a relatively flat disc of insulating material, said disc having an elongated recess, an interrupter element disposed within said recess for repeatedly varying current supplied to the socket, and contacts arranged adjacent opposite sides of the disc and electrically connected with said element.

17. A circuit interrupter adapted to be removably positioned within a lamp socket comprising a relatively flat disc or wafer of insulating material, said disc having a recess interrupting a minor portion of its cross sectional area as measured in a plane parallel to its faces, and an interrupter element disposed within said recess for repeatedly varying current supplied to the socket.

18. A circuit interrupter adapted to be removably positioned within a lamp socket comprising a relatively flat disc shaped body formed substantially entirely of insulating material, said body having a recess, an interrupter element disposed within said recess for repeatedly varying current supplied to the socket, and a pair of metal contacts mounted upon opposite faces of said body and electrically connected to said element, said body serving to electrically insulate said contacts from direct electrical contact with each other.

MILTON H. SHOENBERG.
LESTER SCHON.
